UNITED STATES PATENT OFFICE.

WILLIAM J. RAMSAIER, OF NEW YORK, N. Y.

INK DISTRIBUTOR.

Application filed December 4, 1922. Serial No. 604,912.

To all whom it may concern:

Be it known that I, WILLIAM J. RAMSAIER, a citizen of the United States, and resident of the borough of Manhattan, city, county, and State of New York, have invented certain new and useful Improvements in Ink Distributors, of which the following is a specification.

This invention relates to improvements in ink distributors for printing presses and the like, of the type shown in Patent #1,239,129, dated September 4, 1917.

One of the principal objects of this invention is to provide a sleeve adapted to fit within the roll and having a duplex thread on its inner surface within a crescent-shaped switch carried by the distributor roll supporting shaft operating to impart a reciprocating motion to the roll upon the shaft when the roll is rotated. The sleeve is so constructed that the duplex internal thread is complete within the sleeve at one end thereof, the threads being closed at one end of the sleeve. The other end of the sleeve is closed except that a portion thereof is cut away to form a small entrance giving access to the threads and permitting the crescent switch to be threaded into the sleeve. The entrance opening thus formed is closed by a short segment on the inner surface of which is formed a curved cam surface which serves to complete the thread and to close the entrance to the sleeve.

There are other important objects and advantages of the invention which will appear hereinafter.

In the drawings:

Fig. 1 is a longitudinal sectional view of the distributing roll, the supporting shaft being shown in elevation;

Fig. 2 a detail longitudinal sectional view of one end of the distributing roll, the threaded sleeve and the co-operating parts being shown in side elevation mounted on the supporting shaft but removed from the distributing roll;

Fig. 3 a view similar to Fig. 2 showing the sleeve and co-operating parts assembled and within the distributing roll;

Fig. 4 a transverse sectional view of the roll supporting shaft showing the crescent switch mounted thereon;

Fig. 5 a transverse sectional view of one arm of the crescent switch;

Fig. 6 an end elevation of the threaded sleeve showing the crescent switch partially

inserted in the sleeve through the entrance opening, the supporting shaft being shown in transverse sectional view;

Fig. 7 a detail view of the inner side of 60 the closure segment showing a portion of the duplex thread formed thereon;

Fig. 8 a view similar to Fig. 6 showing the closure segment in position on the end of the threaded sleeve; 65

Fig. 9 a transverse sectional view of the distributing roll taken on the line 9—9 of Fig. 1;

Fig. 10 a longitudinal sectional view of the threaded sleeve showing the upper half 70 thereof;

Fig. 11 a view similar to Fig. 10 showing the lower half thereof;

Fig. 12 a detail view of a portion of the supporting shaft showing the means for 75 locking the crescent switch to the shaft;

Fig. 13 a plan view of the parts shown in Fig. 12, the crescent switch being arranged in position to receive the locking pin; and 80

Fig. 14 a view similar to Fig. 13 the crescent switch being shown in its operative position.

Referring to the various parts by numerals, 1 designates the ink distributor roll 85 which is loosely mounted on a supporting shaft 2.

The shaft 2 may be supported in the press frame in any suitable manner and is held against rotation by any suitable means.

The roll 1 is provided at one end, 90 the left hand end as viewed in Fig. 1 of the drawings, with a suitable bearing 3 adapted to receive the shaft 2.

The bearing 3 is preferably a ring or sleeve of suitable bearing metal extending into the roll and rigidly 95 connected thereto. This bearing is formed with an oil cavity 4 open

to the shaft and designed to deliver oil thereto and with which communication may be had through the passage 5 extending to the 100 outer end surface of the bearing.

In this passage is arranged a spring pressed ball valve 6. In the roll 1, near the right hand end, as shown in Fig. 1, is inserted a bearing 7, said bearing consisting of a ring of suit- 105

able bearing metal forced into the roll and against a slight shoulder 8 and permanently and rigidly connected to the roll. The bearing 7 is arranged within the roll a suitable

distance from the end thereof to form a 110 chamber 9 extending from the said bearing to the adjacent end of the roll. In said

chamber is placed a sleeve 11 having an internal duplex thread 12. Said sleeve fits snugly in the chamber 9 and around the shaft, substantially filling the space between the shaft and the inner surface of the roll. The sleeve 11 is slightly reduced in diameter between the two end parts 11^a and 11^b to form an annular oil space 13 surrounding the sleeve and within the roll. The end portions fit snugly within the roll and accurately center the sleeve therein. In order to secure a uniform distribution of weight of the sleeve 11 around the shaft, the surplus metal may be cut out exteriorly as indicated at 11^c in Figs. 2 and 3.

A pair of locking lugs 14 are formed upon the face of the bearing 7 which is opposed to the sleeve 11 at diametrically opposite points. The sleeve 11 has a pair of slots 15 formed in its inner face opposed to the bearing 7 designed to receive the lugs 14. An interlocking connection is thus provided which compels the sleeve 11 and bearing 7 to rotate together and with the roll. The sleeve is apertured at its ends to receive the supporting shaft which extends longitudinally through it. The duplex thread is closed at the inner end of the sleeve and the two threads are directly connected together so that the crescent switch, which will be presently described, when it reaches the inner end of one thread will be directed by the sleeve itself into the other thread in order to reverse the direction of longitudinal movement of the roll. The outer end of the sleeve is closed except for a segmental entrance opening through which access may be had to the threads and through which the crescent-shape switch may be threaded into the sleeve. This segmental entrance or opening is formed by cutting a short segment or block out of the end of the sleeve; and this opening is adapted to be closed by segmental closure block 16. On the inner face of this closure block is formed a cam surface 17 which, when the closure block is in position completes the duplex thread and completely closes the sleeve except, of course, for the apertures, which receive the supporting shaft. The closure block is formed at diametrically opposite points on its inner face with a pair of locking lugs 18. The opposed face of the sleeve 11 is formed with a pair of slots 19 adapted to receive the lugs 18 and hold the closure block against independent rotative movement. It will be seen that the bearing 7, sleeve 11 and closure block 16 are all connected to rotate with the roll 1.

To cause the roll to reciprocate on the shaft 2, a crescent switch 20 is pivotally or rotatively mounted in an aperture in the shaft and within the sleeve 11. The switch is formed with a stud 21 which fits in a transverse aperture in the shaft, so that the switch is free to oscillate or rotate on the

stud. The two arms are tapered toward their free ends to facilitate travel in the duplex thread as the roll is rotated about its supporting shaft. The inner surfaces of the arms of the switch are cut away toward their free ends to form a slight space between the ends of the arms and the shaft. This is to permit the switch to have a limited free movement on its stud; and the said inner surfaces are slightly rounded, as shown in Fig. 5, to facilitate this movement.

The end of the roll and the end of the chamber 9 is closed by a bearing ring 22, said ring being threaded into the end of the roll with its inner face bearing against the outer face of the sleeve and against the outer face of the closure block 16. A locking screw 23 is threaded through the bearing ring with its inner end engaging the closure block, said screw thereby locking the bearing ring against rotation and also clamping the closure block in position against the end of the sleeve. The inner side of the bearing ring is cut out to form an oil chamber 24. A passage 25 leads from the outer face of the bearing ring into said oil chamber and in said passage 25 is arranged a spring pressed ball valve 26. The oil may be forced into said chamber 24 through said valved passage 25. The internal diameter of the spiral ribs which form the duplex thread is slightly larger than the diameter of the supporting shaft 2 so that the said ribs will not bear on the shaft and a slight space will be formed through which oil from the chamber 24 may readily flow into the sleeve and into the threads formed therein. To permit oil to flow from the interior of the sleeve into the oil chamber 13 surrounding the sleeve small apertures 27 are formed in the sleeve, said apertures leading into the grooves of the duplex thread. The outer face of the bearing 7 is cut out to form a slight oil chamber 28 at the inner end of the threaded sleeve. The chamber 28 is connected by a groove 29 with an oil chamber 30 formed in the bearing 7, said chamber 30 extending entirely around the shaft.

The parts are assembled as shown in Figs. 2 and 3. The supporting shaft is first passed through the bearings 3 and 7. The internally threaded sleeve is then passed over the shaft in position to enter the chamber 9 and beyond the aperture in the shaft adapted to receive the stud of the crescent switch. The crescent switch is then placed in position and the sleeve moved up to it in order to bring the crescent switch to the entrance into the sleeve. The sleeve or the shaft is then rotated to thread the switch into the sleeve, as indicated in Fig. 6. When the sleeve or the shaft has been rotated sufficiently to carry the crescent switch into the sleeve the closure block 16 is placed in position to close the entrance and to complete

the thread. These parts, as thus assembled, are then moved into the chamber 9. The bearing ring 22 is then passed over the end of the shaft and screwed into the threaded 5 end of the roll. The locking screw 23 is then screwed into engagement with the closure block 16, thus locking the bearing ring 22 against rotation and clamping the closure block in position. When the parts are thus 10 all assembled, as illustrated in Fig. 3, the inner end of the sleeve bears against the outer surface of the bearing 7, the lugs 14 are received in the slots 15 and the closure block 17 bears against the outer surface of 15 the sleeve and has its lugs 18 received in the slots 19.

If desired, that portion of the shaft engaged by the arms of the crescent switch may be cut to present a round or semi- 20 spherical surface 31 to the inner surface of the switch arms. This construction is illustrated in Figs. 12, 13 and 14. By this means the crescent arms will be in bearing contact with the shaft at all times while at the same 25 time it may freely follow the duplex thread in the sleeve 11.

To lock the crescent switch to the shaft, to prevent its accidental displacement, a circular recess 32 is formed in the shaft and 20 around the end of the stud of the switch and the walls of this recess are slotted at 33 at diametrically opposite points. Fitted over the end of the stud of the switch and loosely within the recess 32 is a locking collar 34. 25 The stud and the collar are apertured transversely and a pin 35 is passed through said apertures to lock the collar to the stud and thereby secure the switch to the shaft. The apertures in the stud and the collar are so 40 located that when the switch arms are in their extreme lateral position and against the shoulder 36 formed on the shaft, said apertures will be in line with the slots 33 and the locking pin 35 may be readily placed in 45 position. When the switch arms are following the duplex thread within the sleeve the pin 35 will be out of line with the slots 33 and the wall of the recess 32 will hold 50 said pin in position. Said pin can only be removed by disconnecting the switch from the threads of the sleeve 11 and then turning 55 it to its extreme position as shown in Fig. 13. It is manifest that while the switch is in operation within the sleeve it cannot become disconnected from the shaft. It is also manifest that this form of fastening device is desirable should the shaft 2 be rotated and the switch have a tendency to move outwardly away from the shaft.

60 What I claim is:

1. An ink distributor comprising a shaft, a distributing roll slidably mounted on said shaft and formed with a chamber at one end, a sleeve fitted within said chamber and provided with an internal duplex thread, the

ends of said sleeve being apertured to receive the said shaft and the inner ends of the duplex thread being closed and a portion of the outer end of said sleeve being cut away to provide an entrance into the sleeve to give 70 access to the internal duplex thread, a crescent switch pivotally mounted on the shaft and adapted to be passed through the entrance into said sleeve to engage the said internal thread, a block to close the entrance 75 to the sleeve and to complete the thread at the outer end of the sleeve, means for locking the sleeve to the roll to rotate therewith, and means for confining the sleeve within the said chamber. 80

2. An ink distributor comprising a shaft, a distributing roll slidably mounted on said shaft and formed with a chamber at one end, a sleeve fitted within said chamber and provided with an internal duplex thread, 85 the ends of said sleeve being apertured to receive the said shaft and a segmental portion of the outer end of said sleeve being cut away to provide an entrance into the sleeve to give access to the internal duplex thread, 90 a crescent switch pivotally mounted on the shaft and adapted to be passed through the entrance into said sleeve to engage the said internal thread, a segmental block to close the entrance to the sleeve and to complete 95 the duplex thread at the outer end of the sleeve, means for locking the sleeve to the roll to rotate therewith, and means for confining the sleeve within the said chamber.

3. An ink distributor comprising a shaft, a distributing roll slidably mounted on said shaft, a bearing ring rigidly secured within said roll to form a chamber at one end thereof, a sleeve fitted within said chamber and provided with an internal duplex thread 100 and a segmental portion of the outer end of said sleeve being cut away to give access to the internal duplex thread, an interlocking connection between the bearing ring and the sleeve to compel them to rotate together, a 105 crescent switch pivotally mounted on the shaft and adapted to be passed through the opening in the end of the said sleeve and to engage the said internal thread, a segmental block to close the entrance to the sleeve and 110 to complete the duplex thread at the outer end of the sleeve, said segmental block being formed with a locking-lug adapted to enter a slot in the end of said sleeve, and means 115 for confining the sleeve and the segmental 120 block in the chamber.

4. An ink distributor comprising a shaft, a distributing roll slidably mounted on said shaft, a bearing ring rigidly secured within said roll to form a chamber at one end 125 thereof, a sleeve fitted within said chamber and provided with an internal duplex thread and a segmental portion of the outer end of said sleeve being cut away to give access to the internal duplex thread, means to lock 130

4

the sleeve to the said roll, a crescent switch pivotally mounted on the shaft and adapted to be passed through the opening in the end of said sleeve and to engage the said internal thread, a segmental block to close the entrance to the sleeve and to complete the duplex thread at the outer end of the sleeve, said segmental block being formed with a locking lug adapted to enter a slot in the 10 end of the said sleeve, a bearing ring adapted to be screwed into the end of the said roll to confine the sleeve and the segmental block within the said chamber, and means for locking the threaded 15 bearing ring, said locking means being adapted to engage the said segmental block.

5. An ink distributor comprising a shaft, a distributing roll mounted thereon and provided with an internal duplex thread, a 20 crescent switch operating in said thread

and formed with a pivot stud extending through said shaft, said shaft being cut away to form a round, or semi-spherical bearing surface for the inner edge of said crescent switch, a circular socket being 25 formed in said shaft around the free end of said stud, the walls of said socket being slotted at diametrically opposite points, a locking collar fitted to the end of said stud and lying within said socket, said collar and the 30 stud being apertured transversely, and a locking pin fitted in said apertures, said apertures being so located that they are out of line with the said slots in the normal operative position of the switch but may be 35 brought into line of said slots by rotating the switch to an abnormal position.

In testimony whereof I hereunto affix my signature.

WILLIAM J. RAMSAIER.
